UNITED STATES PATENT OFFICE.

JOHN F. APPLEBY, OF MINNEAPOLIS, MINNESOTA, ASSIGNOR TO THE MINNEAPOLIS HARVESTER WORKS, OF MINNESOTA.

GRAIN-BINDER.

SPECIFICATION forming part of Letters Patent No. 256,188, dated April 11, 1882.

Application filed January 31, 1882. (No model.)

To all whom it may concern:

Be it known that I, JOHN F. APPLEBY, of Minneapolis, in the county of Hennepin and State of Minnesota, have invented certain new and useful Improvements in Grain-Binders; and I do hereby declare that the following is a full, clear, and exact description thereof, reference being had to the accompanying drawings, making part of this application.

10 My invention relates to an improved contrivance or means for insuring the stoppage at the right time and in the right position relatively to the driving mechanism thereof of the gears through which power and motion are imparted periodically to the binding mechanism proper of that kind of grain-binders in which the grain passes into and is packed in a gavel-receptacle, and the gavels or collected masses are periodically tied up into sheaves and automatically discharged from the machine.

15 In Letters Patent granted to me February 18, 1879, No. 212,420, is shown a machine of this class, and to this kind of machine, in the improved form in which I have lately used it, 20 I have shown my present improvement applied.

25 As heretofore constructed this kind of machine has embodied the defect of a constant liability to make considerable noise, and have 30 much wear and tear on some of the parts, as well as a liability to have the intermittently-moving parts stop out of time and out of place, owing to the facts, first, that the driving device, when thrown out of engagement with the pinion for driving the binder mechanism proper, left said pinion in a position to have the said continuously-running driving device come into contact with or strike against the part of said pinion last in working engagement with said 35 driving device; and, second, that under the degree of resistance to which the parts of the binder mechanism proper are often subjected said parts would be turned scarcely to the proper point, or, if so turned, would spring or yield 40 back slightly when released from the driving power.

45 My present invention has for its main objects to overcome these defects and render the kind of grain-binders to which said invention is applicable capable of working better; and to this

end and object my invention consists in the combination, with the gear on the cam and rack wheel shaft, of a spring-motor contrivance adapted, as will be hereinafter more fully explained, to cause a given degree of movement 55 of the parts of said mechanism after it shall have ceased to be affected by the usual driving device, whereby not only are the parts of the binder mechanism all carried to and stopped always at precisely the proper point, but whereby, also, the carrying of the gear, acted on by the continuously-running driving device of the harvester, to a point at which a complete clearance of said driving device will be insured is certainly effected.

60 To enable those skilled in the art to fully understand and practice my invention, I will now proceed to more fully describe it, referring by letters to the accompanying drawings, in which—

65 Figure 1 is a partial side elevation of a grain-binder such as made the subject of my said Letters Patent above referred to and as improved and used by me up to the time of my present invention. Fig. 2 is a similar view, 70 showing my present improvement applied to said machine, and so much only of the said machine as it seems to be necessary to show. Fig. 3 is a similar view of the devices seen at Fig. 2, but with the parts in a different relative position; and Fig. 4 is a detail sectional view at the line $x-x$ of Fig. 3.

75 In the several figures the same parts will be found designated by the same reference-letters.

80 With reference to Fig. 1, I need only state that the parts therein shown are about the same as and operate in like manner to the parts of my said patented machine as now used by me, and that E is the main gear on 85 the cam and rack wheel shaft S, and is driven from the continuously-rotating shaft M of the machine through the media of the intermediate pinions or gears, E² E³, and a spur-pinion loose on shaft M, but periodically clutched to 90 said shaft by the dog P, against which work the driving-projections t of the continuously-turning face-plate o, all as already well known.

95 In carrying out my present invention I merely cast the part A⁴ (see Fig. 1) of my ma-

chine with a sort of extension, as seen at A⁵ of Figs. 2 and 3, and vary the form of the casting of gear-wheel E, so as to have it formed with a cam-like rib, as shown at E⁵, Figs. 2 and 3, and I then apply the necessary additional devices as follows:

b² is a metallic stand or piece, formed with a projection at b³, in which is hung one end of a rod, c², the other end of which is pivoted to 10 a lever, d², the said stand b² being bolted to A⁵, and having a lateral lip-like projection, b⁴, (see Fig. 4,) that underlies and bears against a portion of the lower edge of the portion A⁵ of casting A⁴. On the rod c² is a spiral spring, 15 c³, which is compressed between the projection b³ and a collar, c⁵, whenever the said rod may be pushed through projection b³ in the direction indicated by the arrow at Fig. 2 and into the position seen at Fig. 3. The upper 20 end of arm d² is coupled to one end of a rod, f², the other end of which has an oblong eye, f³, that co-operates with two eye-pieces at g, for a purpose to be presently explained, and 25 said arm d² carries at e² a small anti-friction roll, which acts on the cam E⁵ of wheel E in a manner and for the purpose to be presently explained. The height of the roller at e² relatively to the axis of wheel E is easily and nicely adjusted or fixed in putting the machine together by cutting and fitting together 30 the lip-like part b⁴ of stand b² and the edge of A⁵ that fits to said part b⁴, the stand b² turning slightly to permit any necessary adjustment by reason of its pivotal connection 35 at i², and the curved slot (seen in dotted lines at Fig. 2) in the part A⁵.

When properly fitted or adjusted the bolt at j is screwed up and the parts b² and A⁵ securely fastened together.

40 The operation is as follows: Supposing the parts to be in the relative position seen at Fig. 2 and the wheel E to be turning as per arrow indicating its direction of rotation, when the cam-like rib E⁵ comes into contact (not far from its end z) with the roller at e² said roller and the arm d² will be caused to vibrate about the axis of bolt j and in the direction indicated by the arrow at Fig. 2 until the point z of cam E⁵ shall have passed by the 45 bearing-point on the periphery of roller e², at which any movement of the arm d² in the reverse direction (indicated by arrow at Fig. 3) will exert a tendency on the part of said roller to press the cam E⁵ in the direction in which 50 wheel E has been thus far moving. At this point the driving devices (at shaft M, Fig. 1) become disengaged, so as to cease to drive the pinion E³, and but for other means of movement the wheel E would now stop. The pushing 55 tendency of roller e² now, however, comes into play, and, actuated by the powerful spring c³, which has been compressed, the arm d² vibrates in the direction indicated by arrow at Fig. 3 and into the position shown in 60 said figure, thus causing a slight further movement of wheel E and all parts influenced by its movements into a position just such as re-

quired, and in which the engaging surfaces of the driver and the driven devices at shaft M will perfectly clear each other. It will be understood that as soon as the parts shall have been thus forced into the relative position just stated not only will the spring c³ have expended by expansion its greatest force, but the roller e² will have come to a sort of abutment or stop against the ascending surface or portion of the face of cam E⁵, (represented at Figs. 2 and 3 by the circular dotted line,) whereby any further movement through the tendency of the spring c³ is avoided.

When the intermittently-moving parts of the machine are at rest in the positions shown at Fig. 3 the eye f³ of rod f² is in such relationship with the stationary eye g (between which eye f³ is located and moves) that the binder-cord, which passes through all of the said eyes, will not be affected; but when the intermittently-moving parts shall have started off on another movement, and at the beginning of said movement allowed the arm d² 90 and rod f² to have been forced by spring c³ into the position seen at Fig. 2, then the eye f³ will be moved to a position such that the cord, passing through all three of the eyes referred to, will be pulled into a triangular 95 shape by pulling off a larger supply from the ball, and when the parts again resume the relationship seen at Fig. 3 there will be a certain amount of slack, which may be most easily taken up by the binder devices proper in 100 tying a sheaf, and which also serves to prevent any jerk or strain on the cord as the needle-arm (through an eye in which the cord passes, as usual) and other parts all come to a sudden stop. Thus I make the same means 105 which I employ to actuate the gears and force them to stop at just the right time and place also to operate the slack-making device of the binder. Said device is not new in itself 110 in my present machine, but is applied and operated in a novel manner, as just explained.

What I claim as new, and desire to secure by Letters Patent, is—

1. In combination with the intermittently-moving mechanism of the binder and the continuously-running and automatically-unclutching driver devices thereof, means, substantially as described, for causing a slight further movement of said mechanism after its release from the influence of the said driver devices, as set forth.

2. In combination with the automatic mechanism for causing the binder mechanism to move on after its release from the influence of the driver devices of the machine, a 115 rod, f², provided with an eye, f³, and two stationary eyes, g, the whole arranged to operate substantially as and for the purposes set forth.

In testimony whereof I have hereunto set my hand this 12th day of December, 1881.

JOHN F. APPLEBY.

In presence of—

JAMES BURTON,
CHAS. WEAVER.
